APPARATUS FOR TREATING A PERSON'S
HAIR AND SCALP

Louis P. Solos, Chicago, and Vito Re, Cicero, Ill., assignors to Salon at Lincoln Hills, Chicago, Ill., a corporation of Illinois

Filed Dec. 20, 1963, Ser. No. 332,185
16 Claims. (Cl. 128—65)

The present invention relates to apparatus for treating a person's hair and scalp, and more particularly to such apparatus that is cyclically operative to produce a treatment program or cycle including shampooing, rinsing and drying steps.

It is a general object of the invention to provide apparatus of the character noted, that incorporates a circuit network for controlling the automatic program thereof, wherein the control of the circuit network is governed jointly by a program controller of the timer-controlled type and by the person who is receiving the hair and scalp treatment.

Another object of the invention is to provide apparatus of the character noted, that incorporates a manually operable device under the control of a beauty operator for selectively presetting a wide variety of cycle components into the treatment program that is to be carried out by the apparatus.

Another object of the invention is to provide apparatus of the character noted, that includes a helmet that is worn by the person receiving the hair and scalp treatment, wherein the helmet carries all of the operating elements of the apparatus that contact the hair and scalp of the person receiving the treatment.

Another object of the invention is to provide apparatus of the character described, wherein the helmet incorporates an improved arrangement of applicators that are selectively operative to produce the required massage of the person's hair and scalp in the shampooing, rinsing and drying steps of the treatment program.

Another object of the invention is to provide apparatus of the character described, wherein the helmet incorporates an improved sealing arrangement that may be readily fastened and unfastened with respect to a band of the person's head in order to insure a water-tight seal of the chamber defined in the helmet, so as to contain the water and the treatment liquids that are employed in the treatment program.

Another object of the invention is to provide apparatus of the character described, that further comprises chair-like structure including a generally horizontal seat and a back-rest extending upwardly and rearwardly from the rear of the seat, and a pair of upstanding arm-rests respectively disposed at the opposite sides of the seat, wherein the angle of rear inclination of the back-rest with respect to the seat is adjustable to the comfort of the person thus seated in the chair-like structure, wherein the projection of the top of the back-rest above the seat is adjustable to the length of the torso of the person thus seated in the chair-structure, and wherein the helmet previously described is carried by the top central portion of the back-rest, whereby the person may comfortably wear the helmet while the person is comfortably seated in the chair-like structure.

A further object of the invention is to provide apparatus of the character described, wherein certain of the manually operable control facilities for governing the operation of the apparatus are carried on one of the arm-rests and are thus readily accessible to the person seated in the chair-like structure, whereby the person has command of the operation of the apparatus.

A still further object of the invention is to provide ap-

paratus of the character described, wherein the manually operable controls facilities that are carried by the one arm-rest include facility for adjusting the temperature of the water that is employed in the shampooing and rinsing steps thereof, facility for starting and stopping the operation of the applicators that effect the massage in the treatment program, and facility for presetting the mode of operation of the actuators with respect to whether a gentle or brisk massage is to be applied to the person's hair and scalp.

Further features of the invention pertain to the particular construction and arrangement of the elements of the hair and scalp treatment apparatus and to the particular connection and arrangement of the automatic circuit control network therefor, whereby the above-outlined and additional operating features thereof are attained.

The invention, both as to its organization and method of operation, together with further objects and advantages thereof, will best be understood by reference to the following specification, taken in connection with the accompanying drawings, in which:

FIGURE 1 is a fragmentary front perspective view of apparatus for treating a person's hair and scalp and embodying the present invention;

FIGS. 2A and 2B, taken together and respectively arranged left and right in upstanding position, are a vertical sectional view, partly broken away, of a helmet incorporated in the apparatus of FIG. 1;

FIG. 3 is a diagram of a water supply system incorporated in the apparatus of FIG. 1;

FIG. 4 is a diagram of a treatment liquid supply system incorporated in the apparatus of FIG. 1;

FIG. 5 is a diagram of a hot air supply system incorporated in the apparatus of FIG. 1;

FIG. 6 is a diagram of an electric circuit control circuit arrangement incorporated in the apparatus of FIG. 1;

FIG. 7 is an enlarged plan view of the control dial forming a part of a program controller incorporated in the control circuit of FIG. 6;

FIG. 8 is a time-sequence control chart of the control cams carried by the operating shaft of the program controller incorporated in the control circuit of FIG. 6;

FIG. 9 is a vertical sectional view of the helmet, this view being taken in the direction of the arrows along the line 9—9 in FIG. 2B; and

FIG. 10 is a greatly enlarged fragmentary portion of the helmet, taken within the circle 10 in FIG. 9.

Referring now to FIG. 1 of the drawings, there is illustrated apparatus 20 for treating a person's hair and scalp, and embodying the features of the present invention; which apparatus 20 essentially comprises chair-like structure 21 in which the person is seated during the treatment of her scalp. Specifically, the structure 21 includes a supporting base 22, a seat indicated at 23 disposed above the front portion of the base 22, a back-rest indicated at 24 disposed above the intermediate portion of the base 22, and a main housing 25 supported above the rear portion of the base 22. The back-rest 24 is carried by the front or back-structure 26 that is also disposed above the rear portion of the base 22 and that projects from the interior of the housing 25 upwardly and rearwardly therefrom to the exterior and well above the seat 23; and in the arrangement, the bottom of back-rest 24 projects downwardly behind the rear end of the seat 23 and closely adjacent thereto. Also, the structure 21 comprises a pair of upstanding arm-rests 27 disposed above the front portion of the base 22 and positioned adjacent to the opposite sides of the seat 23, the top of each arm-rest carrying an arm-rail, as indicated at 28.

The back-structure 26 carrying the back-rest 24 is adjustable with respect to the base 22, so as suitably to vary the angle, indicated at 29, between the center line

of the back-structure 26 and the vertical, so as correspondingly to adjust the upward and rearward inclination of the back-rest 24 with respect to the seat 23. This mechanism, not shown, is entirely conventional and may be of the well-known spring and counter-weight type; whereby this mechanism includes a position latch provided with a trip button 30. Thus, when the patron, or person, seated in the structure 21 wishes to decrease the angle 29, she leans forwardly and actuates the trip button 30, so that this mechanism causes the back-structure 26 carrying the back-rest 24 to pivot forwardly; which new position of adjustment of the back-structure 26 is preserved upon release of the trip button 30. On the other hand, when the person seated in the structure 21 wishes to increase the angle 29, she leans backwardly and actuates the trip button 30, so as to pivot backwardly the back-structure 26 carrying the back-rest 24; which new position of adjustment of the back-structure 26 is preserved upon release of the trip button 30.

Also, the back-structure 26 carrying the back-rest 24 is adjustable with respect to the base 22, so as suitably to vary the effective height, indicated at 31, between the top of the back-rest 24 and the rear end of the seat 23. This mechanism, not shown, is entirely conventional and may be of the well-known rack and gear type; whereby the mechanism includes a hand-wheel 32. Thus, when it is desirable to adjust the effective height 31 between the top of the back-rest 24 and the rear end of the seat 23, the attendant, or beauty operator, manually rotates the hand-wheel in the required direction in an obvious manner.

Further, the back-structure 26 carries on the front top central portion thereof a helmet 40 that is positioned at the top central portion of the back-rest 24 and that is worn by the person seated in the structure 21 who is to receive the hair and scalp treatment. More particularly, as shown in FIGS. 2A and 2B, the helmet 40 comprises an outer hood or shell 41 that may be formed of a suitable molded synthetic organic resin, such, for example, as the polycarbonate resin sold by the General Electric Co. as "Lexan." The lower front portion of the hood 41 has a substantially annular opening 41a formed therein that accommodates the insertion therethrough of the upper and rear portions of the person's head, so that the hood 41 encloses the person's hair and scalp.

Before proceeding with the description of the construction and arrangement of the helmet 40, it is first noted that the person who is to receive the hair and scalp treatment is first seated in the structure 21. The inclination or angle 29 of the back-rest 24 with respect to the vertical is then adjusted to the comfort of the person; and then the height 31 of the top of the back-rest 24 above the seat 23 is adjusted to the length of the person's torso, and specifically to cause the helmet 40 to enclose the hair and scalp of the person thus comfortably seated in the structure 21.

Returning to the construction of the helmet, and again referring to FIGS. 2A and 2B, the extreme top end of back-rest 24 carries a cushion 24a that is adapted to engage the nape of the neck of the person comfortably seated in the structure 21, when the height of the top of the back-rest 24 is properly adjusted above the rear end of the seat 23, so as comfortably to support the person's head in upright position while the top and rear portions thereof are enclosed by the hood 41. The edge about the opening 41a formed into the lower front portion of the hood 41 is suitably reinforced by a metal band 42 that may be formed of stainless steel; and, in turn, the band 42 carries a composite flexible sealing gasket 43 of generally annular form and that is adapted to engage an annular band of the person's head disposed adjacent to the person's hairline, thereby to form a substantially liquid-tight seal between the hood 41 and the engaged annular band of the person's head and to define a chamber 41a within the hood 41 and disposed above

and rearwardly of the corresponding upper and rear portions of the person's head thus enclosed in the hood 41. Also, the sealing gasket 43 is so constructed and arranged that it spaces the band 42 radially outwardly from the person's head, so as to accommodate limited turning of the person's head with respect to her torso and with respect to the hood 41 while the person is thus seated comfortably in the structure 21 and is thus wearing the helmet 40, and without impairing the liquid-tight seal between the hood 41 and the engaged annular band of the person's head. More particularly, the composite annular sealing gasket 43 comprises a substantially annular flexible and elastic head band 44 that may be formed of latex, or the like, and having the general construction of the band usually provided about a bathing cap; which head band 44 that may be formed of latex, or the like, and having the general construction of the band usually provided about a bathing cap; which head band 44 directly engages the band about the person's head at her hairline, as previously noted. The elastic band 44 is suitably secured as by an adhesive, in water-tight relation to the inner edge of an annular diaphragm 45 formed of a flexible sheet of water-impermeable synthetic organic resin, such, for example, as the polyethylene terephthalate resin sold by Du Pont as "Mylar." The outer edge of the annular diaphragm 45 is detachably secured in water-tight relation to the metal band 42 employing a number of snap-fasteners, indicated at 46. The extreme front and rear portions of the outer edge of the diaphragm 45 are suitably secured in water-tight relation to the respectively adjacent portions of the hood 41 by snap-fasteners, respectively indicated at 47 and 48. Thus, it will be understood that the arrangement of the snap-fasteners 46, 47 and 48 accommodates ready placement and removal of the composite sealing gasket 43 with respect to the hood 41 and within the opening 41a formed therein. This arrangement is very advantageous, as frequent replacement of the composite sealing gasket 43 not only insure proper operation thereof to perform its water-sealing function, but insures that the same is maintained in a clean and sanitary condition at all times. As a matter of fact, a new sealing gasket 43 may be employed for each hair and scalp treatment and then discarded, without substantial expense. Finally, an elastic O-ring 49 formed of synthetic rubber, or the like, is sandwiched or placed between the elastic band 44 and the adjacent inner portion of the diaphragm 45, so as positively to insure a water-tight seal by the sealing gasket 43 with the engaged band of the person's head.

The rear and top central portions of the helmet 40 carry rigid metal structures including a generally horizontal beam 50 and a generally vertical column 51, the front end of the beam 50 being secured to the top central portion of the hood 41 by a suitable fastener 52, the intermediate portions of the column 51 being fastened to the rear central portion of the hood 41 by two brackets 53 and 54, and the rear end of the beam 50 and the top end of the column 51 being rigidly secured together, as by welding.

An operating rod 55 is mounted on top of the beam 50 for reciprocation along a generally horizontal axis and fore-and-aft with respect to the top central portion of the hood 41 by an arrangement including front and rear brackets 56 and 57 respectively securely fastened to the corresponding ends of the beam 50, the operating rod 55 projecting through aligned guide bearings, not shown, respectively carried by the brackets 56 and 57. In order to prevent turning or rotating of the operating rod 55 incident to reciprocation thereof, a guide pin 58 is carried by the operating rod 55 and arranged to project forwardly through a cooperating guide hole formed in the rear bracket 57. The guide pin 58 may be formed of a suitable molded plastic resin, such, for example, as the polytetrafluoroethylene resin sold by Du Pont as "Teflon." More particularly, the rear end of the guide

pin 58 is fixed to a clamp 59 that, in turn, is securely fastened to the operating rod 55 rearwardly of the rear bracket 57. Also, a clamp 60 is securely fastened to the operating rod 55 forwardly of the front bracket 56. The operating rod 55 is biased into a centered position with respect to the brackets 56 and 57 by two surrounding coil springs 61 and 62, the coil spring 61 acting between the front bracket 56 and the adjacent clamp 60, and the coil spring 62 acting between the rear bracket 57 and the adjacent clamp 59. The rear portion of the operating rod 55 is provided with teeth and constitutes a rack 63 that meshes a cooperating gear 64 that is fixed to the upper end of an upstanding shaft 65 mounted for rotation upon upper and lower bearing brackets 66 and 67 that are rigid fixed to the upper portion of the column 51; and the lower end of the shaft 65 has a V-pulley 68 fixed thereto.

In view of the foregoing, it will be understood that rotation of the shaft 65 first in one direction and then in the opposite direction, and through corresponding angles of rotation, will effect reciprocation of the operating rod 55 fore and aft with respect to its centered position and respectively against the bias of the coil springs 62 and 61; whereby the coil springs 61 and 62 tend to maintain the operating rod 55 in its centered position.

An operating rod 69 is mounted on the rear side of the column 51 for reciprocation along a generally vertical axis and up and down with respect to the rear central portion of the hood 41 by an arrangement including upper and lower brackets 70 and 71 respectively securely fastened to the intermediate and lower portions of the column 51, the operating rod 69 projecting through aligned guide bearings 72 respectively carried by the brackets 70 and 71. The operating rod 69 is biased into a down position by a coil spring 73 surrounding the top end thereof, the top of the coil spring 73 being fixed to the extreme top end of the operating rod 69, and the bottom of the coil spring 73 being fixed to a retainer 74 that, in turn, is fixed to the adjacent portion of the column 51. The extreme bottom end of the operating rod 69 carried a rotatably mounted cam follower 75 that engages an eccentric cam 76 carried by the operating shaft 77 of an electric drive motor 78. The intermediate portion of the operating rod 69 is provided with teeth and constitutes a rack 79 that meshes a cooperating gear 80 that is fixed to the rear end of a substantially horizontally disposed shaft 81 mounted for rotation upon a pair of bearing elements 82 carried by a bearing housing 83 that is securely fastened to the front side of the column 51.

In view of the foregoing, it will be understood that operation of the electric drive motor 78 effects rotation of its operating shaft 77 and the eccentric cam 76 carried thereby, whereby the cam follower 75 in rolling engagement with the outer surface of the eccentric cam 76 effects reciprocation of the operating rod 69. Specifically, the operating rod 69 moves upwardly against the bias of the coil spring 73, and moves downwardly by the action of gravity and by the action of the coil spring 73. As the operating rod 69 is thus reciprocated, the rack 79 meshing the gear 80 causes rotation of the shaft 81 first in one direction and then in the other, whereby the shaft 81 is thus oscillated about its horizontal longitudinal axis and through suitable angles from a neutral position, as established by the stroke of the operating rod 69, as determined by the eccentricity of the eccentric cam 76.

The extreme rear end of the shaft 81 has a pulley 84 fixed thereto; and a drive connection, including an endless belt 85, is provided between the pulley 84 fixed to the shaft 81 and the pulley 68 fixed to the shaft 65. The intermediate section of the belt 85 is trained over two spaced-apart guide pulleys 86 that are carried by bracket structure 87 secured to the adjacent portion of the column 51. The guide pulleys 86 respectively engage the opposite runs of the intermediate portion of the belt 85

and are arranged at the intersection of the horizontal plane of the pulley 68 and the vertical plane of the pulley 84.

Accordingly, the previously described rotary oscillation of the shaft 81 effects the previously described reciprocation of the operating rod 55, through the drive connection including the pulley 84, the belt 85 and the pulley 68, together with the shaft 65 the gear 64 and the rack 63. Hence, the operation of the drive motor 78 effects rotary oscillation of the shaft 81 and longitudinal or axial oscillation of the operating rod 55 for purposes described hereinafter.

Arranged in the upper central portion of the chamber 41a and above the top portion of the head of the person wearing the helmet 40 is a first applicator 90 having a generally inverted U-shaped configuration, as shown in FIGS. 2B, 9 and 10. More particularly, the applicator 90 comprises an inner metal spring 91 carrying an inner liner 92 formed of latex, synthetic rubber, or other soft material, and an outer metal reinforcing spring 93, the inner spring 91 being securely fastened to the outer spring 93 in any suitable manner, and the inner liner 92 being secured, as by adhesive, to the inner spring 91. Also, the inner liner 92 carries a plurality of spaced-apart and radially inwardly projecting scrubbing fingers or tips 94 that are of soft flexible construction and that are adapted directly to engage the adjacent top and side portions of the hair and scalp of the person wearing the helmet 40. The elements 91, 92 and 93 are perforated, as indicated at 95, so that water and treatment liquids may readily penetrate the applicator 90 from the exterior and effect contact with the tips 94 and with the hair and scalp of the person wearing the helmet 40. The central portion of the outer spring 93 is rigidly secured to an upwardly directed rod 96 that is adjustably carried in the lower open end of a cooperating upstanding tube 97, rotation of the rod 96 relative to the tube 97 being prevented by a cross pin 98 disposed in a slot formed in the tube 97 and extending through a hole provided in the upper end of the rod 96, and vertical adjustment of the rod 96 relative to the lower end of the tube 97 being effected by a nut 99 carried by a threaded lower outer surface of the tube 97 and cooperating with the pin 98. The upper end of the rod 96 is retained in depressed position with respect to the lower end of the tube 97 by a cooperating coil spring 100 arranged within the tube 97 and engaging the upper end of the rod 96. The extreme upper end of the tube 97 terminates in a sleeve 101 that is mounted upon the extreme front end of the operating rod 55; which sleeve 101 is located in a pocket 41c provided in the top front central portion of the hood 41 and defined by a corresponding upstanding dome section 41d of the hood 41, the pocket 41c being in open communication with the upper central portion of the chamber 41a, as best shown in FIG. 2B.

More particularly, the front portion of the operating rod 55 projects forwardly through a hole provided in the rear wall of the dome section 41d and into the pocket 41c; which hole is rendered liquid-tight by an annular sealing grommet 102 carried by the adjacent rear wall of the dome section 41d and disposed in sealed relation with the section of the operating rod 55 projecting therethrough. The sleeve 101 is adjustable longitudinally along the front end of the operating rod 55 and within the pocket 41c; and any adjusted position of the sleeve 101 may be retained by a set screw 103 carried thereby and frictionally engaging the front end of the operating rod 55.

In view of the foregoing, it will be understood that the previously described axial oscillation of the operating rod 55 is imparted to the sleeve 101 carried thereby and arranged in the pocket 41c, and thus to the applicator 90 carried by the sleeve 101 and arranged in the upper front portion of the chamber 41a. At this time, the tips 94 carried by the inner liner 92 are in engagement with the hair and scalp of the person wearing the helmet

40; whereby a corresponding fore-and-aft massage is applied to the front and top portions of the hair and scalp of the person by this oscillation of the applicator 90.

Arranged in the rear portion of the chamber 41a and rearwardly of the rear portion of the head of the person wearing the helmet 40 is a second applicator 110, having a generally dished-shaped configuration, as shown in FIG. 2B. The applicator 110 is of the fundamental construction of the applicator 90 described in detail above; whereby the applicator 110 comprises the elements 111, 112, 113, 114 and 115, respectively corresponding to the elements 91, 92, 93, 94 and 95 of the applicator 90; whereby these elements 111, etc., are not here described in detail in the interest of brevity. Thus, it will be understood that the soft flexible fingers or tips 114 are adapted directly to engage the adjacent rear portions of the hair and scalp of the person wearing the helmet 40. The central portion of the outer spring 113 is rigidly secured to a rearwardly directed spindle 116 disposed in a generally horizontal position of alignment with the shaft 81. The rear end of the spindle 116 is adjustably carried in the front open end of a cooperating tube 117, rotation of the spindle 116 relative to the tube 117 being prevented by a cross pin 118 disposed in a slot 117a formed in the tube 117 and extend through a hole provided in the rear end of the spindle 116, and longitudinal adjustment of the spindle 116 relative to the front end of the tube 117 being effected by a nut 119 carried by the threaded front outer surface of the tube 117 and cooperating with the pin 118. The rear end of the spindle 116 is forwardly thrust position with respect to the front end of the tube 117 by a cooperating coil spring 120 arranged within the tube 117 and engaging the rear end of the spindle 116. The extreme rear end of the tube 117 is rigidly fixed to a bracket 121 that is mounted upon the extreme front end of the shaft 81; which bracket 121 is located in the extreme rear central portion of the chamber 41a defined within the hood 41.

More particularly the front portion of the shaft 81 projects forwardly through a hole provided in the rear central portion of the hood 41; which hole is rendered liquid-tight by an annular sealing grommet 122 carried by the adjacent rear wall of the hood 41 and disposed in sealed relation with the section of the shaft 81 projecting therethrough. The bracket 121 comprises a pair of rearwardly directed arms 123 between which a guide pin 124 projects and through a hole formed in the front end of the shaft 81, thereby to connect the shaft 81 to the tube 117 via the bracket 121. Also, an adjusting screw 125 is rotatably mounted between the arms 123 and forwardly of the guide pin 124; which screw 125 engages a threaded hole provided in the extreme front end of the shaft 81; whereby the position of axial alignment between the shaft 81 and the tube 117 may be adjusted by proper rotation of the screw 125 in an obvious manner. Finally, one end of the screw 125 carries a knurled part 126, so as to accommodate ready manual adjustment of the screw 125.

In view of the foregoing, it will be understood that the previously described rotary oscillation of the shaft 81 is imparted to the bracket 121 arranged in the extreme rear of the chamber 41a, and thus to the applicator 110 arranged in the rear portion of the chamber 41a. At this time, the tips 114 carried by the inner liner 112 are in engagement with the hair and scalp of the person wearing the helmet 40; whereby a corresponding rotary oscillatory massage is applied to the rear portion of the hair and scalp of the person by this oscillation of the applicator 110.

By way of recapitulation, it is noted that when the chair-like structure 21 is adjusted to suit the comfort of the person who is to receive the hair and scalp treatment, the positions of the applicators 90 and 110 within the hood 41 may also be adjusted to the comfort of the person. Specifically, the vertical position of the applicator

90 within the upper front portion of the chamber 41a may be adjusted by proper manipulation of the nut 99 with respect to the tube 97. Similarly, the horizontal position of the applicator 110 within the rear portion of the chamber 41a may be adjusted by proper manipulation of the nut 119 with respect to the tube 117. These adjustments of the nuts 99 and 119 are made by the attendant or beauty operator to the comfort of the patron or person who is to receive the hair and scalp treatment.

Referring now to FIGS. 1, 2A, 2B and 3, the apparatus 20 further comprises a water supply system including a hot water supply pipe 131 containing hot water under gauge pressure, a cold water supply pipe 132 containing cold water under gauge pressure, a hot water valve 133 disposed in the hot water pipe 131, a cold water valve 134 disposed in the cold water pipe 132, a warm water supply pipe 135, and a mixing valve 136 provided with two inlets respectively connected to the pipes 131 and 132 and an outlet connected to the pipe 135. The valve 133 is of the solenoid-operated type, the solenoid of which is indicated at 133a; and the valve 133 is normally biased into its closed position and is operated into its open position in response to energization of the solenoid 133a. The valve 134 is of the solenoid-operated type, the solenoid of which is indicated at 134a; and the valve 134 is normally biased into its closed position and is operated into its open position in response to energization of the solenoid 134a. The mixing valve 136 is of the thermostatic controlled type and includes a manually operable dial 137 cooperating with an associated index marker 138 and selectively operative to preset the desired temperature of the warm water delivered therefrom to the pipe 135. Thus, when the valves 133 and 134 are opened, both the hot water and cold water are delivered to the mixing valve 136; whereby the thermostatic facility incorporated in the mixing valve 136 operates to cause mixing of the hot water and the cold water to produce warm water in the pipe 135 and having a temperature corresponding to that preset by the dial 137; which mixing valve 136 is of a conventional type.

The hood 41 carries a pair of side nozzles 141 adjacent to the opposite upper sides thereof that are respectively directed downwardly and inwardly toward the opposite upper sides of the applicator 90, and carries a rear nozzle 142 adjacent the rear lower central portion thereof that is directed upwardly and inwardly toward the central portion of the applicator 110. Each of the nozzles 141 and 142 is of the ball-socket type so that it can be adjusted with respect to the direction thereof; each of the nozzles 141 is suitably supported by a base 143 rigidly secured in place in a corresponding hole provided in the side wall of the hood 41; the nozzle 142 is suitably supported by a base 144 rigidly secured in place in a hole provided in the rear wall of the hood 41; each of the nozzles 141 is provided with a water supply tube, not shown, that is connected to the warm water pipe 135; and the nozzle 142 is provided with a water supply tube 145 that is connected to the warm water pipe 135. Thus, when the valves 133 and 134 are opened warm water from the pipe 135 is supplied to the nozzles 141 and 142; the two side nozzles 141 direct two side streams of water onto the opposite sides of the perforated applicator 90; and the rear nozzle 142 directs a rear stream of water onto the central portion of the perforated applicator 110.

Referring now to FIGS. 1, 2B, 4 and 6, the apparatus 20 further comprises a treatment liquids supply system including a number of shampoo liquid reservoirs SR1 to SR7, inclusive, a corresponding number of shampoo liquid dispensers SD1 to SD7, inclusive, a number of rinse liquid reservoirs RR1 to RR4, inclusive, and a corresponding number of rinse liquid dispensers RD1 to RD4, inclusive. The shampoo liquid reservoirs SR1, etc., are adapted to contain corresponding different liquid shampoos and are respectively connected to the corresponding shampoo liquid dispensers SD1, etc.; and the

shampoo liquid dispensers SD1, etc., are commonly connected to a liquid shampoo supply pipe 151. The rinse liquid reservoirs RR1, etc., are adapted to contain corresponding different liquid cream rinses and are respectively connected to the corresponding rinse liquid dispensers RD1, etc.; and the rinse liquid dispensers RD1, etc., are commonly connected to a liquid rinse supply pipe 152. The shampoo liquid dispensers SD1, etc., are of the solenoid-operated type and are respectively provided with the corresponding operating solenoids SD1S to SD7S, inclusive; and similarly, the rinse liquid dispensers RD1, etc., are of the solenoid-operated type and are respectively provided with the corresponding operating solenoids RD1S to RD4S, inclusive. Energization of any one of the solenoids SD1S, etc., effects the discharge from the associated shampoo liquid dispenser SD1, etc., of a measured charge of liquid shampoo into the shampoo supply pipe 151; and subsequent deenergization of the solenoid SD1S causes the associated shampoo liquid dispenser SD1 to receive another charge of liquid shampoo from the associated shampoo liquid reservoir SR1. Similarly, energization of any one of the solenoids RD1S, etc., effects the discharge from the associated rinse liquid dispenser RD1, etc., of a measured charge of liquid cream rinse into the rinse supply pipe 152; and subsequent deenergization of the solenoid RD1S causes the associated rinse liquid dispenser RD1 to receive another charge of liquid rinse from the associated rinse liquid reservoir RR1.

The shampoo supply pipe 151 and the rinse supply pipe 152 are commonly connected to a treatment liquid supply pipe 153; and the outer end of the pipe 153 projects through a hole provided in the top central portion of the hood 41 and terminates in a treatment nozzle 154 arranged in the upper portion of the chamber 41a. The hole in the wall of the hood 41 through which the pipe 153 projects is rendered liquid-tight by a grommet 155 carried by the adjacent wall of the hood 41 and disposed in sealed engagement with the section of the pipe 153 projecting therethrough. The treatment nozzle 154 is directed downwardly toward the rear central portion of the perforated applicator 90.

In view of the foregoing, it will be understood that when one of the shampoo liquid dispensers SD1, etc., pumps a charge of liquid shampoo into the pipe 151, the same passes therefrom via the pipe 153 and into the nozzle 154; whereby the liquid shampoo is directed by the nozzle 154 in a stream onto the perforated applicator 90. Similarly, when one of the rinse liquid dispensers RD1, etc., pumps a charge of liquid cream rinse into the pipe 152, the same passes therefrom via the pipe 153 and into the nozzle 154; whereby the liquid cream rinse is directed by the nozzle 154 in a stream onto the perforated applicator 90.

Referring now to FIGS. 1, 2A, 2B and 5, it will be observed that the extreme lower rear portion of the chamber 41a formed in the hood 41 communicates directly with the upper open end of a drain tube 160 disposed just rearwardly of the cushion 24a carried by the extreme top end of the back-rest 24; whereby the water, liquid shampoos and liquid cream rinses projected into the chamber 41a drain from the lower rear portion thereof into the upper open end of the drain tube 160. The drain tube 160 is of flexible construction and formed of any suitable material, such as synthetic rubber. Also, the drain tube 160 extends through the back-structure 26 into the housing 25; and the lower open end of the drain tube 160 communicates with a basin or sump 161 arranged in the housing 25. In turn, the water, liquids, etc., accumulating in the sump 161 are removed therefrom by a drain pump 162 that is driven by an electric motor 163. In the arrangement, the inlet of the pump 162 communicates with the sump 161 via a pipe 164 and the outlet of the pump 162 is connected to a duct or tube 165 extending to drain plumbing, not shown.

Referring now to FIGS. 1, 2A, and 5, it is noted that

the apparatus 20 further comprises a hot air supply system that includes a blower or fan 170 that is driven by an electric motor 171. In the arrangement, a shroud 172 is operatively associated with the fan 170; which shroud 172 preferably contains a suitable electric heater 173 and is provided with an inlet 174 communicating with the atmosphere and an outlet 175 communicating with the lower open end of an air duct 176. The air duct 176 may be formed of a suitable flexible tubing that is preferably odorless and insensitive to hot air. The elements 170, 171, 172 and 173 are arranged in the housing 25 and the air duct 176 extends upwardly through the back-structure 26 to the helmet 40. Specifically, the upper open end of the air duct 176 communicates with an opening formed in the upper rear central portion of the hood 41, the upper end of the air duct 176 being secured in place upon the adjacent rear wall of the hood 41 by a cooperating ring 177 carrying fasteners, indicated at 178 in FIG. 2A. Also, a perforated baffle 179 is arranged in the upper rear portion of the chamber 41a forwardly of the upper open end of the air duct 176 and rearwardly and above the applicator 110; which baffle 179 is secured to the hood 41, as by screws 179, and prevents the blast of hot air that is admitted into the rear portion of the chamber 41a out of the air duct 176 from impinging directly upon the hair and scalp of the person seated in the chair-like structure 21 and wearing the helmet 40.

In view of the foregoing, it will be understood that the air which is taken into the shroud 172 by operation of the fan 170 is heated by the electric heater 173 and then blown through the air duct 176 into the rear portion of the chamber 41a and onto the baffle 179. The hot air passes through the perforated baffle 179 and into contact with the hair and scalp of the person wearing the helmet 40 and then passes downwardly through the drain tube 160 into the sump 161. The hot air escapes from the open top of the sump 161 into the interior of the housing 25.

In the arrangement, the air inlet 174 into the shroud 172 may communicate with a series of lower louvers 181 formed in a wall of the housing 25, as shown in FIG. 1, and via a passage containing a removable drawer 182, as indicated in FIG. 1; which drawer 182 may contain a suitable filter, not shown; whereby the air passes through the lower louvers 181 and thence through the filter contained in the removable drawer 182 and then into the inlet 174 of the shroud 172. This arrangement is very advantageous, as it insures that no dust or lint is entrained in the air that is subsequently heated by the electric heater 173 and then passed via the air duct 176 into the chamber 41a in the helmet 40. The hot air that escapes from the open top of the sump 161 into the interior of the housing 25 may pass therefrom back to the exterior via another series of lower louvers 183 formed in the wall of the housing 25, as shown in FIG. 1.

Referring now to FIG. 6, the apparatus 20 further comprises a control circuit that incorporates a program controller 200 that is provided with a rotatably mounted operating shaft 201 carrying a manually operable control dial 202 rigidly secured to the outer end thereof, which dial 202 cooperates with an associated index marker 203. Also, the operating shaft carries a plurality of insulating cams C1, C2, C3, C4, C5 and C6 rigidly fixed thereto, and that respectively control a plurality of armature springs S1, S2, S3, S4, S5 and S6. The spring S1 governs associated front and back switch springs S11 and S12; the spring S3 governs associated front and back switch springs S31 and S32; and the springs S2, S4, S5 and S6 respectively govern front switch springs S21, S41, S51 and S61.

Also, the operating shaft 201 is mounted for longitudinal axial movement, as well as for the rotary movement previously described; whereby the operating shaft 201 carries a contact bridging member 204 that is adapted selectively to bridge an associated pair of front contacts and constituting a line switch. More particularly, when

the manual dial 202 is depressed, moved inwardly toward the index marker 203, the operating shaft 201 is moved longitudinally inwardly so as to actuate the line switch 204 into its open position; conversely, when the manual dial 202 is withdrawn, pulled outwardly away from the index marker 203, the operating shaft 201 is moved longitudinally outwardly so as to actuate the line switch 204 into its closed position.

Also, the program controller 200 comprises a shaft 205 that is mounted only for rotary movement; and the outer end of the shaft 205 is connected to the adjacent inner end of the operating shaft 201 by an associated sleeve-like connector 205' that accommodates the relative longitudinal axial sliding movements of the operating shaft 201 with respect to the shaft 205, while maintaining the normal rotary connection therebetween. Further, the program controller 200 comprises a timer motor TM of the synchronous type, and preferably a "Telechron" motor. The timer motor TM comprises an operating shaft 206 that is connected to an escapement mechanism 207 that is provided with a driven shaft 207'; and the shafts 207' and 206 are connected together by a friction clutch 208. The friction clutch 208 accommodates manual rotation of the operating shaft 201 by the manual dial 202, without interference by the escapement mechanism 207. In the arrangement, operation of the timer motor TM may cause the escapement mechanism 207 to index the shaft 207' through an angle of 5° each 30 seconds in the counter clockwise direction in a well-known manner.

Considering now in greater detail the control circuit, as illustrated in FIG. 6, the same comprises a terminal block, not shown, to which a source of electric power supply of 118-volts, 60 cycles, single-phase, A-C, is connected; this source including an ungrounded conductor 211 and a grounded conductor 212. Also the circuit includes an interlock or master switch MS, one pole of which is connected to the line conductor 211 and the other pole of which is connected to a conductor 212. The contacts of the line switch 204 respectively terminate the conductor 212 and a conductor 213; and the conductor 213 is commonly terminated by the armature springs S1, S2, S3, S4, S5 and S6. The switch springs S11, S12, S21, S31, S32, S41, S51, and S61 respectively terminate conductors 214, 215, 216, 217, 218, 219, 220 and 221.

Further, the circuit comprises a number of manually operable shampoo selector switches SS1 to SS7, inclusive, respectively corresponding to the solenoids SD1S to SD7S, inclusive, and a number of manually operable rinse selector switches RS1 to RS4, inclusive, respectively corresponding to the solenoids RD1S to RD4S, inclusive. Also, the circuit comprises a speed preset device 230 for presetting the speed of operation of the main motor 78, thereby to set the frequency of oscillation of the applicators 90 and 110; which speed preset device 130 consists essentially of a variable resistor 231, an associated shorting wiper 232, a rotatably mounted operating shaft 233 for selectively adjusting the shorting position of the wiper 232 with respect to the resistor 231, and a manual control dial 234 for selectively rotating the operating shaft 233, the control dial 234 cooperating with an associated index marker 235.

In the circuit; the main motor is bridged across the conductors 220 and 221; the terminals of the resistor 231 are bridged across the line conductor 210 and the conductor 221; the wiper 232 is connected to the line conductor 210; the pump motor 163 is bridged across the line conductor 210 and the conductor 219; the fan motor 171 and the electric heater 173 are bridged in parallel relation across the line conductor 210 and the conductor 218; the cold solenoid 134a is bridged across the line conductor 210 and the conductor 217; and the hot solenoid 133a is bridged across the line conductor 210 and the conductor 216. First terminals of the sole-

noids SD1S to SD7S, inclusive, are commonly connected to the conductor 215; the second terminals of these solenoids are respectively connected to first poles of the corresponding select switches SS1 to SS7, inclusive; and the second poles of these switches are commonly connected to the line conductor 210. First terminals of the solenoids RD1S to RD4S, inclusive, are commonly connected to the conductor 214; the second terminals of these solenoids are respectively connected to first poles of the corresponding select switches RS1 to RS4, inclusive; and the second poles of these switches are commonly connected to the line conductor 210.

Considering now the general arrangement of the control equipment: the master switch MS may be advantageously arranged on the arm-rail 28 carried by the right-hand arm-rest 27 of the chair-like structure 21, as shown in FIG. 1, so that the patron or person seated in the structure 21 and wearing the helmet 40 may at any time arrest the program that is being carried out by the apparatus 20 merely by operating the master switch MS into its open position in a convenient and obvious manner. Similarly, the manual dial 137 of the thermostatic mixing valve 136 that presets the temperature of the warm water that is supplied to the nozzles 141 and 142 in the helmet 40 may be carried by the right-hand arm-rest 27, so that this adjustment may be conveniently made by the patron while seated in the structure 21. Similarly, the manual dial 234 of the speed preset device 230 that establishes the speed of the main motor 78 and consequently the frequency of oscillation of the applicators 90 and 110 arranged in the helmet 40 may be carried by the right-hand arm-rest 27, so that this adjustment may be conveniently made by the patron while seated in the structure 21. The top wall of the housing 25 may carry a plate 190 disposed just rearwardly of the right-hand arm-rest 27 and the corresponding side of the back-rest 24, as shown in FIG. 1; which plate 190 may carry the manual dial 202 of the program controller 200, the bank of shampoo selector switches SS1 to SS7, inclusive, and the bank of rinse selector switches RS1 to RS4, inclusive; which elements 202, SS1, etc. and RS1, etc., are normally operated by the attendant or beauty operator. Also, in the arrangement of the apparatus 20, the helmet 40 merges into the back-structure 26, at the junction therebetween, as shown in FIG. 1, so that none of the operating mechanism for the applicators 90 and 110 arranged in the helmet 40 are exposed, but rather are housed in the adjacent upper and front portions of the back-structure 26. Thus, all of the operating mechanisms and moving elements forming a part of the apparatus 20 are housed either in the back-structure 26 or in the housing 25, so that the chair-like structure 21 has a finished appearance and generally resembles a large upholstered library chair.

Turning now to FIGS. 7 and 8, it will be understood that four independent hair and scalp treatment programs are incorporated in the control cams C1 to C6, inclusive; which programs have been designated: Selection-1, Selection-2, Selection-3 and Selection-4. Accordingly, the control dial 202 comprises four start positions and four coordinate stop positions and four coordinate groups of control positions, as illustrated in FIG. 7, and respectively corresponding to the four programs. Selection-1 is the most comprehensive program and comprises a wetting cycle, a first shampoo cycle, a first water rinse cycle, a second shampoo cycle, a second water rinse cycle, a cream rinse cycle, a third water rinse cycle and a drying cycle; this program consuming 9½ minutes. Selection-2 is a less comprehensive program and comprises a wetting cycle, a first shampoo cycle, a first water rinse cycle, a second shampoo cycle, a second water rinse cycle and a drying cycle; this program consuming 8½ minutes. Selection-3 is a still less comprehensive program and comprises a wetting cycle, a shampoo cycle, a first water rinse cycle, a cream rinse cycle, a second water rinse cycle and a drying cycle; this program consuming 6½ minutes. Selection-4 is the least comprehensive program and com-

prises a wetting cycle, a shampoo cycle, a water rinse cycle and a drying cycle; this program consuming 5½ minutes.

The time sequence of the various cycles included in each of the four selections as well as the time durations of each of the included cycles will be readily apparent from an examination of the time-sequence chart of FIG. 8.

Considering now in detail the carrying out of one of the four programs, such, for example, as Selection-1, the beauty operator first selects the one or more ingredients that are to comprise the shampoo liquid to be employed and then closes the one or more corresponding switches SS1, SS2, etc. Also, the beauty operator selects the one or more ingredients that are to comprise the cream rinse liquid to be employed and then closes the one or more corresponding switches RS1, RS2, etc. Next the beauty operator rotates the dial 202 of the program controller 200 into the start position for Selection-1, while the dial 202 occupies its depressed position. It may also be assumed that the patron is comfortably seated in the chair structure 21 and is comfortably wearing the helmet 40, all in the manner previously explained. The beauty operator assists the patron with adjusting the dial 137 to the expected comfortable warm water temperature and with adjusting the dial 234 to the expected comfortable frequency of oscillation of the applicators 90 and 110 incorporated in the helmet 40. When this has been accomplished, the beauty operator lifts the dial 202 in order to cause the operating shaft 201 of the program controller 200 to close the line switch 204. The beauty operator then advises the patron that she may start the preselected program (Selection-1) when she is ready merely by closing the master switch MS. Of course, the beauty operator explains to the patron the controls involving the dials 137 and 234, and notes to her that she may stop and restart the program at any time by control of the master switch MS. It is contemplated that the master switch MS is of a conventional construction, so that upon each operation or striking of its operating plate or button carried by the arm-rail 28, the master switch MS is actuated between its switch positions. Thus, each odd strike of this button closes the master switch MS and each even strike of this button opens the master switch MS in a well-known manner.

When the patron closes the master switch MS, at this time, the line conductor 211 is connected to the conductor 212 and via the line switch 204 in its closed position to the conductor 213. Connection of potential to the conductor 213 completes a circuit including the elements S6, S61, 221 and 210 for energizing the timer motor TM so as to initiate operation thereof and the consequent timing of the present preset program. Neglecting the controls, for the present, the timer motor TM operates the escapement mechanism 207 via the drive shaft 206; whereby the escapement mechanism 207 indexes the driven shaft 207' step by step each 30 seconds through successive angles of 5° each; with the result that the operating shaft 201 is rotated step by step in the counter clockwise direction and into its coordinate stop position at the conclusion of the program. Also, at the conclusion of the program, the switch springs S6, S61 are opened to interrupt the circuit for operating the timer motor TM. Also, at this time, the beauty operator depresses the dial 202 to insure opening of the line switch 204 so as positively to prevent closure of any of the control circuits.

Considering now the controls that are carried out in the preselected program (Selection-1), in position #1 of the operating shaft 201, the sets of switch springs S2, S21, and S3, S31 and S4, S41 are closed, as illustrated by the "x" in each of the corresponding boxes in the chart of FIG. 8. Closure of the switch springs S2, 21 completes a circuit including the elements 211, MS, 212, 204, 213, S2, S21, 216 and 210 for energizing the hot solenoid 133a, so as to effect opening of the hot water valve 133. Closure of the switch springs S3, S31 completes a circuit

including the elements 211, MS, 212, 204, 213, S3, S31, 217 and 210 for energizing the cold solenoid 134a, so as to effect opening of the cold water valve 134. Thus, hot water and cold water are supplied to the mixing valve 136, whereby warm water at the temperature preset by the dial 137 is supplied into the pipe 135 and consequently to the nozzles 141 and 142, so that the three streams of water are projected onto the applicators 90 and 110 in the helmet 40. Of course this effects wetting of the patron's hair and scalp; and the water runs from the chamber 41a via the drain tube 160 into the sump 161. Closure of the switch springs S4, S41 completes a circuit including the elements 211, MS, 212, 204, 213, S4, S41, 219 and 210 for operating the pump motor 163. The motor 163 operates the pump 162, whereby the water accumulating in the sump 161 is pumped via the tube 165 to the drain plumbing, not shown.

In position #2 of the operating shaft 201, the switch springs S2, S21 and S3, S31 are opened to cause deenergization of the solenoids 133a and 134a, so as to effect closure of the valves 133 and 134, thereby to cut-off the supply of water to the nozzles 141 and 142. Also, in position #2 of the operating shaft 201, the switch springs S1, S12 and S5, S51 are closed. Closure of switch springs S1, S12 completes parallel circuits for the several solenoids SD1S, SD2S, etc., corresponding to the closed shampoo selector switches SS1, SS2, etc. These circuits include the common elements 211, MS, 212, 204, 213, S1, S12, 215 and 210, and respectively include the elements SS1, SS2, etc.; whereby the several shampoo dispensers SD1, SD2, etc., are operated to effect the pumping of liquid shampoo therefrom via the pipes 151 and 153 to the treatment nozzle 154 in the helmet 40, whereby the liquid shampoo is directed by the nozzle 154 onto the applicator 90 and thus onto the patron's hair and scalp. Closure of the switch springs S5, S51 completes a circuit including the elements 211, MS, 212, 204, 213, S5, S51, 220, 221, 231 and 210 for operating the main motor 78; whereby oscillation of the applicators 90 and 110 in the helmet 40 are initiated. Of course, the liquid shampoo and the water in the patron's wet hair produce a lather and the oscillating applicators 90 and 100 shampoo and massage the patron's hair and scalp. It will be appreciated that the above traced circuit for operating the main motor 78 includes at least a portion of the series related resistor 231; whereby the speed of operation of the main motor 78 is inversely related to the part of the resistor 231 that is included in series relation therewith as is determined by the position of the wiper 232. Thus adjustment of the manual dial 234 governs the speed of the main motor 78 in an obvious manner; and the frequency of oscillation of the applicators 90 and 110 is dependent upon the speed of operation of the main motor 78. Accordingly, the arrangement permits the manual dial 234 to adjust the frequency of oscillation of the applicators 90 and 110 to the comfort of the patron receiving the present treatment. Naturally, a relatively high frequency of oscillation of the applicators 90 and 110 produces a more vigorous massage with respect to the hair and scalp of the patron, in an obvious manner.

In position #3 of the operating shaft 201, the switch springs S1, S12 are opened in order to interrupt the previously traced circuits for energizing the several solenoids SD1S, SD2S, etc., which operation is without effect in the present program, except that the deenergization of the solenoids SD1S, etc., causes the associated shampoo dispensers SD1S, etc., to operate in order to receive another charge of the liquid shampoo from the associated shampoo reservoirs SR1, etc.

In position #4 of the operating shaft 201, the switch springs S2, S21 and S3, S31 are reclosed, so as to effect reopening of the valves 133 and 134, in the manner previously described, with the result that the warm water is again projected from the nozzles 141 and 142 onto the oscillating applicators 90 and 110 in the helmet 40 so as thoroughly to rinse the hair and scalp of the patron.

In passing, it is mentioned that in the event the temperature of this warm water is not to the comfort of the patron, she may adjust the same by proper manipulation of the control dial 137, in the manner previously explained. The above described water rinsing cycle continues until the operating shaft 201 is rotated into position #8; wherein the switch springs S2, S21 and S3, S31 are opened, so as to effect reclosure of the valves 133 and 134, in order to terminate this water rinsing cycle. Also, in position #8 of the operating shaft 201, the switch springs S1, S12 are closed, thereby to effect reoperation of each one of the preselected shampoo dispensers SD1, etc., with the result that shampoo is again delivered from the treatment nozzle 154 onto the oscillating applicator 90 and consequently upon the patron's hair and scalp. Of course, the liquid shampoo and the water in the patron's wet hair again produce a lather and the consequent shampooing and massaging of the patron's hair and scalp.

In position #9, the switch springs S1, S12 are opened, so as again to cause the preselected shampoo dispensers SD1, etc., to cycle, so as to receive additional charges of liquid shampoo from the associated shampoo reservoirs SR1, etc.

In position #10 of the operating shaft 201, the switch springs S2, S21 and S3, S31 are reclosed, so as to effect reopening of the valves 133 and 134, with the result that the warm water is again projected from the nozzles 141 and 142 onto the oscillating applicators 90 and 110, so as thoroughly to rinse the hair and scalp of the patron. The above described water rinsing cycle continues until the operating shaft 201 is rotated into position #14; wherein the switch springs S2, S21 and S3, S31 are opened, so as to effect reclosure of the valves 133 and 134 in order to terminate this water rinsing cycle. Also in position #14 of the operating shaft 201, the switch springs S1, S11 are closed. Closure of the switch springs S1, S11 completes parallel circuits for the several solenoids RD1S, RD2S, etc., corresponding to the closed rinse selector switches RS1, RS2, etc. These circuits include the common elements 211, MS, 212, 213, S1, S11, 214 and 210, and respectively include the elements RS1, RS2, etc., whereby the several rinse dispensers RD1, RD2, etc., are operated to effect the pumping of liquid cream rinse therefrom via the pipes 152 and 153 to the treatment nozzle 154 in the helmet 40, whereby the liquid cream rinse is directed by the nozzle 154 onto the applicator 90 and thus onto the patron's hair and scalp.

In position #15 of the operating shaft 201, the switch springs S1, S11 are opened in order to interrupt the previously traced circuits for energizing the several solenoids RD1S, RD2S, etc., which operation is without effect in the present program, except that the deenergization of the solenoids RD1S, etc. causes the associated rinse dispensers RD1, etc., to operate in order to receive another charge of the liquid cream rinse from the associated rinse reservoirs RR1, etc.

Also in position #15 of the operating shaft 201, the switch springs S2, S21, and S3, S31 are reclosed so as to effect reopening of the valves 133 and 134, with the result that the warm water is again projected from the nozzles 141 and 142 onto the oscillating applicators 90 and 110 so as thoroughly to rinse the liquid cream rinse from the patron's hair and scalp.

In position #16 of the operating shaft 201, the switch springs S2, S21 and S3, S31 and S5, S51 are opened. Opening of the switch springs S2, S21 and S3, S31 effects reclosure of the valves 133 and 134 in order to terminate this water rinsing cycle. Also the opening of the switch springs S5, S51 interrupts the circuit for operating the main motor 78, with the result that further oscillation of the applicators 90 and 110 in the helmet 40 is arrested at this time.

Also in position #16 of the operating shaft 201, the switch springs S3, S32 are closed so as to complete parallel circuits including the elements 211MS, 212, 204, 213, S3,

S32, 218 and 210 for operating the fan motor 171 and for energizing the electric heater 173. Thus, the fan motor 171 circulates outside air over the air filter arranged in the removable drawer 182 and thence into the shroud 172 and over the electric heater 173 and via the air duct 176 into the chamber 41a in the helmet 40 and thence via the drain duct 160 into the sump 161 and thence into the housing 25 and therefrom back to the outside. Of course, the electric heater 173 heats this current of air that is thus delivered into the helmet 40; whereby the blast of hot air gently penetrates the perforated baffle 179 and contacts the patron's hair so as to effect a drying action thereupon.

In position #18 of the operating shaft 201, the switch springs S4, S41 are opened so as to deenergize the pump motor 163 in order to arrest operation of the pump 162 by virtue of the fact that by this time all of the water that has been received by the sump 161 has been pumped via the tube 165 to the drain plumbing, not shown.

The drying cycle continues until the operating shaft 201 is rotated into position #20, whereupon the switch springs S3, S32 are opened in order to arrest operation of the fan motor 171 and to deenergize the electric heater 173. At this time, the cycle has been completed and the operating shaft in position #20 occupies its "stop" position coordinate to the "start" position #1 of this Selection-1, as previously explained; whereby the program of Selection-1 is completed.

At this time, the beauty operator may assist the patron with the removal of the helmet 40, whereby the patron vacates the chair-like structure 21 and proceeds to another site in the beauty shop, wherein her hair may be set or other hair-processing procedures carried out with respect thereto.

In view of the foregoing explanation of the mode of operation of the apparatus 20, in order to carry out the preselected program of Selection-1, it will be understood that the other preset programs corresponding to Selection-2, etc., are carried out in a substantially identical manner in response to corresponding setting of the manual dial 202 of the program controller 200 into its coordinate start position for the other preselected program Selection-2, etc.

In passing, it is mentioned that at any time the patron seated in the chair-like structure 21 and wearing the helmet 40 may interrupt the preset program by momentary operation of the master switch MS and may subsequently restart the preset program at the exact point where it was interrupted by again operating the master switch MS; all without unduly disturbing the carrying out of the overall preset program. Further, it is noted that during the carrying out of a preset program, the patron has some freedom of movement of her head relative to her torso and to the helmet 40, notwithstanding the oscillating of the applicators 90 and 110 in carrying out the cycles in the helmet 40 that are effected in the program in the manner previously explained. This freedom mentioned is possible by virtue of the construction of the composite sealing gasket 43 arranged between the band about the patron's head and the hood 41 and by virtue of the mounting arrangements of the applicators 90 and 110 upon the respective tubes 97 and 117, as previously explained.

In view of the foregoing, it is apparent that there has been provided improved apparatus for treating a person's hair and scalp that is selectively operative to carry out a program including preselected cycles, including wetting, shampooing, water rinsing, cream rinsing and drying cycles, wherein the preselection may include desired repetition of one or more of the cycles mentioned. Also, the apparatus comprises an improved arrangement of the operating mechanism incorporated in a helmet forming a part of the apparatus. The apparatus further comprises an improved arrangement of chair-like structure and the helmet mentioned, both forming a part of the overall apparatus.

While there has been described what is at present con-

sidered to be the preferred embodiment of the invention, it will be understood that various modifications may be made therein, and it is intended to cover in the appended claims all such modifications as fall within the true spirit and scope of the invention.

What is claimed is:

1. Apparatus for treating a person's hair and scalp, comprising a helmet having a substantially annular opening in the lower front portion thereof accommodating the insertion therethrough of the upper and rear portions of the person's head so as to enclose in said helmet the person's hair and scalp, a substantially annular sealing gasket carried by said helmet and surrounding said opening and adapted to engage an annular band of the person's head disposed adjacent to the person's hairline, thereby to form a substantially liquid-tight seal between said helmet and the engaged annular band of the person's head and to define a chamber within said helmet disposed above and rearwardly of the upper and rear portions of the person's head thus enclosed in said helmet, a plurality of water nozzles carried by said helmet and disposed in spaced-apart relation in said chamber and adapted to project a corresponding plurality of water streams onto the person's hair and scalp, means selectively operative to supply water to said water nozzles, a treatment nozzle carried by said helmet and disposed in the upper portion of said chamber and adapted to project a charge of treatment liquid onto the person's hair and scalp, means selectively operative to supply treatment liquid to said treatment nozzle, a drain tube carried by said helmet and communicating with the lower rear portion of said chamber adjacent to the nape of the person's neck so as to accommodate draining of water and treatment liquid from said chamber to the exterior, a first applicator arranged in the upper portion of said chamber and mounted upon said helmet for first cyclic reciprocatory movement fore-and-aft with respect thereto and along a first generally horizontal axis, said first applicator being adapted to engage the upper portion of the person's hair and scalp so as to effect a corresponding first reciprocatory mode of massage fore-and-aft thereof, a second applicator arranged in the rear portion of said chamber and mounted upon said helmet for second cyclic oscillatory rotary movement left-and-right with respect thereto and about a second generally horizontal axis, said second applicator being adapted to engage the rear portion of the person's hair and scalp so as to effect a corresponding second oscillatory rotary mode of massage left-and-right thereof, mechanical means operative to impart said first cyclic movement to said first applicator and to impart said second cyclic movement to said second applicator, and a motor selectively operative to operate said mechanical means.

2. The apparatus set forth in claim 1, and further comprising a program controller including an operating shaft mounted for rotation and having a start position and a group of control positions and a stop position, manually operable means for rotating said shaft into its start position, timer means for rotating said shaft from its start position through its group of control positions and then into its stop position upon a timed basis, and a circuit network controlled by rotation of said shaft through its group of control positions for selectively operating said water supply means and said treatment liquid supply means and said motor so as to produce a timed operating program for said apparatus.

3. The apparatus set forth in claim 1, and further comprising a program controller including an operating shaft mounted for rotation and having a number of start positions and a number of groups of control positions and a number of stop positions, manually operable means for rotating said shaft into any one of its start positions, timer means for rotating said shaft from its one start position through its associated one group of control positions and then into its associated one stop position, and a circuit network controlled by rotation of said shaft through its

one group of control positions for selectively operating said water supply means and said treatment liquid supply means and said motor so as to produce a corresponding one timed operating program for said apparatus, whereby 5 said apparatus has a number of timed operating programs respectively corresponding to said number of groups of control positions, and wherein said operating programs are different from each other with respect to the operating components included therein.

10 4. The apparatus set forth in claim 1, wherein said first applicator is of plate-like form and has a plurality of perforations therein to accommodate the ready passage therethrough of the water and the treatment liquid projected thereonto, and said second applicator is of plate-like form and has a plurality of perforations therein to 15 accommodate the ready passage therethrough of the water projected thereonto.

5. The apparatus set forth in claim 1, and further comprising a conduit.

20 6. The apparatus set forth in claim 5, and further comprising a perforated baffle arranged in the upper and rear portions of said chamber above and rearwardly of said first and second applications and supported by said helmet for distributing the heated air stream delivered 25 through said conduit into said chamber.

7. The apparatus set forth in claim 5, and further comprising a sump communicating with the outer end of said drain tube for separating the water and the air passing from said chamber through said drain tube and for accumulating the separated water, and a pump operative to discharge water from said sump to drain.

30 8. Apparatus for treating a person's hair and scalp, comprising a helmet having a substantially annular opening in the lower front portion thereof accommodating the insertion therethrough of the upper and rear portions of the person's head so as to enclose in said helmet the person's hair and scalp, a substantially annular sealing gasket carried by said helmet and surrounding said opening and adapted to engage an annular band of the person's head disposed adjacent to the person's hairline, thereby to form a substantially liquid-tight seal between said helmet and the engaged annular band of the person's head and to define a chamber within said helmet disposed above and rearwardly of the upper and rear portions of the person's head thus enclosed in said helmet, a plurality of water nozzles carried by said helmet and disposed in spaced-apart relation in said chamber and adapted to project a corresponding plurality of water streams onto the person's hair and scalp, a hot water pipe, a cold water pipe, a thermostatic control valve having a hot water inlet connected to said hot water pipe and a cold water inlet connected to said cold water pipe and a warm water outlet, said control valve also including a manually operable device for presetting the desired 40 temperature of the warm water in said warm water outlet, said control valve being selectively controlled automatically to supply into said warm water outlet warm water at the temperature preset by said control device, means selectively operative to supply water from said 45 warm water outlet to said water nozzles, a treatment nozzle carried by said helmet and disposed in the upper portion of said chamber and adapted to project a charge of treatment liquid onto the person's hair and scalp, means selectively operative to supply treatment liquid to said 50 treatment nozzle, a drain tube carried by said helmet and communicating with the lower rear portion of said chamber adjacent to the nape of the person's neck so as to accommodate draining of water and treatment liquid from said chamber to the exterior, a first applicator arranged 55 in the upper portion of said chamber and mounted upon said helmet for first cyclic reciprocatory movement fore-and-aft with respect thereto and along a first generally horizontal axis, said first applicator being adapted to engage the upper portion of the person's hair and scalp so 60 as to effect a corresponding first reciprocatory mode of 65 treatment liquid onto the person's hair and scalp, means selectively operative to supply treatment liquid to said treatment nozzle, a drain tube carried by said helmet and communicating with the lower rear portion of said chamber adjacent to the nape of the person's neck so as to accommodate draining of water and treatment liquid from said chamber to the exterior, a first applicator arranged 70 in the upper portion of said chamber and mounted upon said helmet for first cyclic reciprocatory movement fore-and-aft with respect thereto and along a first generally horizontal axis, said first applicator being adapted to engage the upper portion of the person's hair and scalp so 75 as to effect a corresponding first reciprocatory mode of

massage fore-and-aft thereof, a second applicator arranged in the rear portion of said chamber and mounted upon said helmet for second cyclic oscillatory rotary movement left-and-right with respect thereto and about a second generally horizontal axis, said second applicator being adapted to engage the rear portion of the person's head and scalp so as to effect a corresponding second oscillatory rotary mode of massage left-and-right thereof, mechanical means operative to impart said first cyclic movement to said first applicator and to impart said second cyclic movement to said second applicator, and a motor selectively operative to operate said mechanical means.

9. Apparatus for treating a person's hair and scalp, comprising chair-like structure including a generally horizontal seat and a back-rest extending upwardly and rearwardly from the rear of said seat and a pair of upstanding arm-rests respectively disposed at the opposite sides of said seat, means for adjusting the angle of rear inclination of said back-rest with respect to said seat to the comfort of the person thus seated in said chair-like structure, means for adjusting the projection of the top of said back-rest above said seat to the length of the torso of the person thus seated in said chair-like structure, a helmet carried by the top central portion of said back-rest, said helmet having a substantially annular opening in the lower front portion thereof accommodating the insertion therethrough of the upper and rear portions of the person's head when the person is thus seated comfortably in said chair-like structure so as to enclose in said helmet the person's hair and scalp, a substantially annular sealing gasket carried by said helmet and surrounding said opening and adapted to engage an annular band of the person's head disposed adjacent to the person's hairline, thereby to form a substantially liquid-tight seal between said helmet and the engaged annular band of the person's head and to define a chamber within said helmet disposed above and rearwardly of the upper and rear portions of the person's head thus enclosed in said helmet, said gasket also spacing said helmet radially outwardly from the person's head so as to accommodate comfortable limited turning of the person's head with respect to the person's torso and with respect to said helmet while the person is thus seated comfortably in said chair-like structure and is thus wearing said helmet, a plurality of water nozzles carried by said helmet and disposed in spaced-apart relation in said chamber and adapted to project a corresponding plurality of water streams onto the person's hair and scalp, means selectively operative to supply water to said water nozzles, a treatment nozzle carried by said helmet and disposed in the upper portion of said chamber and adapted to project a charge of treatment liquid onto the person's hair and scalp, means selectively operative to supply a treatment liquid to said treatment nozzle, a drain tube carried by said helmet and communicating with the lower rear portion of said chamber adjacent to the nape of the person's neck so as to accommodate draining of water and treatment liquid from said chamber to the exterior, a first applicator arranged in the upper portion of said chamber and mounted upon said helmet for first cyclic movement with respect thereto and adapted to engage the upper portion of the person's hair and scalp so as to effect massage thereof, a second applicator arranged in the rear portion of said chamber and mounted upon said helmet for second cyclic movement with respect thereto and adapted to engage the rear portion of the person's hair and scalp so as to effect massage thereof, mechanical means operative to impart said first cyclic movement to said first applicator and to impart said second cyclic movement to said second applicator, and a motor selectively operative to operate said mechanical means.

10. Apparatus for treating a person's hair and scalp, comprising chair-like structure including a generally horizontal seat and a back-rest extending upwardly and rear-

wardly from the rear of said seat and a pair of upstanding arm-rests respectively disposed at the opposite sides of said seat, means for adjusting the angle of rear inclination of said back-rest with respect to said seat to the comfort of the person thus seated in said chair-like structure, means for adjusting the projection of the top of said back-rest above said seat to the length of the torso of the person thus seated in said chair-like structure, a helmet carried by the top central portion of said back-rest, said helmet having a substantially annular opening in the lower front portion thereof accommodating the insertion therethrough of the upper and rear portions of the person's head when the person is thus seated comfortably in said chair-like structure so as to enclose in said helmet the person's hair and scalp, a substantially annular sealing gasket carried by said helmet and surrounding said opening and adapted to engage an annular band of the person's head disposed adjacent to the person's hairline, thereby to form a substantially liquid-tight seal between said helmet and the engaged annular band of the person's head and to define a chamber within said helmet disposed above and rearwardly of the upper and rear portions of the person's head thus enclosed in said helmet, said gasket also spacing said helmet radially outwardly from the person's head so as to accommodate comfortable limited turning of the person's head with respect to the person's torso and with respect to said helmet while the person is thus seated comfortably in said chair-like structure and is thus wearing said helmet, a plurality of water nozzles carried by said helmet and disposed in spaced-apart relation in said chamber and adapted to project a corresponding plurality of water streams onto the person's hair and scalp, means selectively operative to supply water to said water nozzles, a treatment nozzle carried by said helmet and disposed in the upper portion of said chamber and adapted to project a charge of treatment liquid onto the person's hair and scalp, means selectively operative to supply a treatment liquid to said treatment nozzle, a drain tube carried by said helmet and communicating with the lower rear portion of said chamber adjacent to the nape of the person's neck so as to accommodate draining of water and treatment liquid from said chamber to the exterior, a first applicator arranged in the upper portion of said chamber and mounted upon said helmet for first cyclic movement with respect thereto and adapted to engage the upper portion of the person's hair and scalp so as to effect massage thereof, a second applicator arranged in the rear portion of said chamber and mounted upon said helmet for second cyclic movement with respect thereto and adapted to engage the rear portion of the person's hair and scalp so as to effect massage thereof, mechanical means operative to impart said first cyclic movement to said first applicator and to impart said second cyclic movement to said second applicator, an electric motor selectively operative to operate said mechanical means, an electric circuit for operating said motor, and a control switch in said circuit, said control switch being carried by one of said arm-rests and in readily accessible position for selective control by the person thus seated in said chair-like structure and thus wearing said helmet, whereby the person may start and stop operation of said motor in order correspondingly to start and stop said massages.

11. Apparatus for treating a person's hair and scalp, comprising chair-like structure including a generally horizontal seat and a back-rest extending upwardly and rearwardly from the rear of said seat and a pair of upstanding arm-rests respectively disposed at the opposite sides of said seat, means for adjusting the angle of the rear inclination of said back-rest with respect to said seat to the comfort of the person thus seated in said chair-like structure, means for adjusting the projection of the top of said back-rest above said seat to the length of the torso of the person thus seated in said chair-like structure, a helmet carried by the top central portion of said back-rest, said helmet having a substantially annular opening in the

lower front portion thereof accommodating the insertion therethrough of the upper and rear portions of the person's head when the person is thus seated comfortably in said chair-like structure so as to enclose in said helmet the person's hair and scalp, a substantially annular sealing gasket carried by said helmet and surrounding said opening and adapted to engage an annular band of the person's head disposed adjacent to the person's hairline, thereby to form a substantially liquid-tight seal between said helmet and the engaged annular band of the person's head and to define a chamber within said helmet disposed above and rearwardly of the upper and rear portions of the person's head thus enclosed in said helmet, said gasket also spacing said helmet radially outwardly from the person's head so as to accommodate comfortable limited turning of the person's head with respect to the person's torso and with respect to said helmet while the person is thus seated comfortably in said chair-like structure and is thus wearing said helmet, a plurality of water nozzles carried by said helmet and disposed in spaced-apart relation in said chamber and adapted to project a corresponding plurality of water streams onto the person's hair and scalp, means selectively operative to supply water to said water nozzles, a treatment nozzle carried by said helmet and disposed in the upper portion of said chamber and adapted to project a charge of treatment liquid onto the person's hair and scalp, means selectively operative to supply a treatment liquid to said treatment nozzle, a drain tube carried by said helmet and communicating with the lower rear portion of said chamber adjacent to the nape of the person's neck so as to accommodate draining of water and treatment liquid from said chamber to the exterior, a first applicator arranged in the upper portion of said chamber and mounted upon said helmet for first cyclic movement with respect thereto and adapted to engage the upper portion of the person's hair and scalp so as to effect massage thereof, a second applicator arranged in the rear portion of said chamber and mounted upon said helmet for second cyclic movement with respect thereto and adapted to engage the rear portion of the person's hair and scalp so as to effect massage thereof, mechanical means operative to impart said first cyclic movement to said first applicator and to impart said second cyclic movement to said second applicator, an electric motor selectively operative to operate said mechanical means, an electric circuit for operating said motor, a speed controller in said circuit, said speed controller being carried by one of said arm-rests and in readily accessible position for selective control by the person thus seated in said chair-like structure and thus wearing said helmet, whereby the person may adjust the speed of operation of said motor in order correspondingly to adjust the speed of said massages.

12. Apparatus for treating a person's hair and scalp, comprising chair-like structure including a generally horizontal seat and a back-rest extending upwardly and rearwardly from the rear of said seat and a pair of upstanding arm-rests respectively disposed at the opposite sides of said seat, means for adjusting the angle of rear inclination of said back-rest with respect to said seat to the comfort of the person thus seated in said chair-like structure, means for adjusting the projection of the top of said back-rest above said seat to the length of the torso of the person thus seated in said chair-like structure, a helmet carried by the top central portion of said back rest, said helmet having a substantially annular opening in the lower front portion thereof accommodating the insertion therethrough of the upper and rear portions of the person's head when the person is thus seated comfortably in said chair-like structure so as to enclose in said helmet the person's hair and scalp, a substantially annular sealing gasket carried by said helmet and surrounding said opening and adapted to engage an annular band of the person's head disposed adjacent to the person's hairline, thereby to form a substantially liquid-tight seal between

said helmet and the engaged annular band of the person's head and to define a chamber within said helmet disposed above and rearwardly of the upper and rear portions of the person's head thus enclosed in said helmet, said gasket also spacing said helmet radially outwardly from the person's head so as to accommodate comfortable limited turning of the person's head with respect to the person's torso and with respect to said helmet while the person is thus seated comfortably in said chair-like structure and is thus wearing said helmet, a plurality of water nozzles carried by said helmet and disposed in spaced-apart relation in said chamber and adapted to project a corresponding plurality of water streams onto the person's hair and scalp, a hot water pipe, a cold water pipe, a thermostatic control valve having a hot water inlet connected to said hot water pipe and a cold water inlet connected to said cold water pipe and a warm water outlet, said control valve also including a manually operable device for presetting the desired temperature of the warm water in said warm water outlet, said control valve being selectively controlled automatically to supply into said warm water outlet warm water at the temperature preset by said control device, means selectively operative to supply water from said warm water outlet to said water nozzles, a treatment nozzle carried by said helmet and disposed in the upper portion of said chamber and adapted to project a charge of treatment liquid onto the person's hair and scalp, means selectively operative to supply treatment liquid to said treatment nozzle, a drain tube carried by said helmet and communicating with the lower rear portion of said chamber adjacent to the nape of the person's neck so as to accommodate draining of water and treatment liquid from said chamber to the exterior, a first applicator arranged in the upper portion of said chamber and mounted upon said helmet for first cyclic movement with respect thereto and adapted to engage the upper portion of the person's hair and scalp so as to effect massage thereof, a second applicator arranged in the rear portion of said chamber and mounted upon said helmet for second cyclic movement with respect thereto and adapted to engage the rear portion of the person's hair and scalp so as to effect massage thereof, mechanical means operative to impart said first cyclic movement to said first applicator and to impart said second cyclic movement to said second applicator, and a motor selectively operative to operate said mechanical means, said control device being carried by one of said arm-rests and in readily accessible position for selective control by the person thus seated in said chair-like structure and wearing said helmet, whereby the person may adjust the temperature of the warm water employed in said massages.

13. Apparatus for treating a person's hair and scalp, comprising chair-like structure including a generally horizontal seat and a back-rest extending upwardly and rearwardly from the rear of said seat and a pair of upstanding arm-rests respectively disposed at the opposite sides of said seat, means for adjusting the angle of rear inclination of said back-rest with respect to said seat to the comfort of the person thus seated in said chair-like structure, means for adjusting the projection of the top of said back-rest above said seat to the length of the torso of the person thus seated in said chair-like structure, a helmet carried by the top central portion of said back rest, said helmet having a substantially annular opening in the lower front portion thereof accommodating the insertion therethrough of the upper and rear portions of the person's head when the person is thus seated comfortably in said chair-like structure so as to enclose in said helmet the person's hair and scalp, a substantially annular sealing gasket carried by said helmet and surrounding said opening and adapted to engage an annular band of the person's head disposed adjacent to the person's hairline, thereby to form a substantially liquid-tight seal between

seal between said helmet and the engaged annular band of the person's head and to define a chamber within said helmet disposed above and rearwardly of the upper and rear portions of the person's head thus enclosed in said helmet, said gasket also spacing said helmet radially outwardly from the person's head so as to accommodate comfortable limited turning of the person's head with respect to the person's torso and with respect to said helmet while the person is thus seated comfortably in said chair-like structure and is thus wearing said helmet, a plurality of water nozzles carried by said helmet and disposed in spaced-apart relation in said chamber and adapted to project a corresponding plurality of water streams onto the person's hair and scalp, means selectively operative to supply water to said water nozzles, a treatment nozzle carried by said helmet and disposed in the upper portion of said chamber and adapted to project a charge of treatment liquid onto the person's hair and scalp, means selectively operative to supply treatment liquid to said treatment nozzle, a drain tube carried by said helmet and communicating with the lower rear portion of said chamber adjacent to the nape of the person's neck so as to accommodate draining of water and treatment liquid from said chamber to the exterior, a first applicator arranged in the upper portion of said chamber and mounted upon said helmet for first cyclic movement with respect thereto and adapted to engage the upper portion of the person's hair and scalp so as to effect massage thereof, a second applicator arranged in the rear portion of said chamber and mounted upon said helmet for second cyclic movement with respect thereto and adapted to engage the rear portion of the person's hair and scalp so as to effect massage thereof, mechanical means operative to impart said first cyclic movement to said first applicator and to impart said second cyclic movement to said second applicator, a motor selectively operative to operate said mechanical means, a conduit carried by said helmet and communicating with the upper rear portion of said chamber, a blower operative to deliver outside air in a stream through said conduit and into said chamber, whereby the air stream is circulated through said chamber into contact with the person's hair and scalp and thence via said drain tube and back to the outside, and a heater operative to heat the air stream delivered through said conduit into said chamber.

14. The apparatus set forth in claim 13, and further comprising a program controller for selectively operating said water supply means and said treatment liquid supply means and said motor and said blower and said heater in a predetermined cycle so as to produce a hair and scalp treatment cycle for said apparatus and including given washing and shampooing and rinsing and drying steps.

15. Apparatus for treating a person's hair and scalp, comprising chair-like structure including a generally horizontal seat and a back-rest extending upwardly and rearwardly from the rear of said seat and a pair of upstanding arm-rests respectively disposed at the opposite sides of said seat, means for adjusting the angle of rear inclination of said back-rest with respect to said seat to the comfort of the person thus seated in said chair-like structure, means for adjusting the projection of the top of said back-rest above said seat to the length of the torso of the person thus seated in said chair-like structure, a helmet carried by the top central portion of said back rest, said helmet having a substantially annular opening in the lower front portion thereof accommodating the insertion therethrough of the upper and rear portions of the person's head when the person is thus seated comfortably in said chair-like structure so as to enclose in said helmet the person's hair and scalp, a substantially

annular sealing gasket carried by said helmet and surrounding said opening and adapted to engage an annular band of the person's head disposed adjacent to the person's hairline, thereby to form a substantially liquid-tight seal between said helmet and the engaged annular band of the person's head and to define a chamber within said helmet disposed above and rearwardly of the upper and rear portions of the person's head thus enclosed in said helmet, said gasket also spacing said helmet radially outwardly from the person's head so as to accommodate comfortable limited turning of the person's head with respect to the person's torso and with respect to said helmet while the person is thus seated comfortably in said chair-like structure and is thus wearing said helmet, said sealing gasket being detachably secured in place in sealed relation with said helmet so as to accommodate ready replacement of said sealing gasket, a plurality of water nozzles carried by said helmet and disposed in spaced-apart relation in said chamber and adapted to project a corresponding plurality of water streams onto the person's hair and scalp, means selectively operative to supply water to said water nozzles, a treatment nozzle carried by said helmet and disposed in the upper portion of said chamber and adapted to project a charge of treatment liquid onto the person's hair and scalp, means selectively operative to supply treatment liquid to said treatment nozzle, a drain tube carried by said helmet and communicating with the lower rear portion of said chamber adjacent to the nape of the person's neck so as to accommodate draining of water and treatment liquid from said chamber to the exterior, a first applicator arranged in the upper portion of said chamber and mounted upon said helmet for first cyclic movement with respect thereto and adapted to engage the upper portion of the person's hair and scalp so as to effect massage thereof, a second applicator arranged in the rear portion of said chamber and mounted upon said helmet for second cyclic movement with respect thereto and adapted to engage the rear portion of the person's hair and scalp so as to effect massage thereof, mechanical means operative to impart said first cyclic movement to said first applicator and to impart said second cyclic movement to said second applicator, a motor selectively operative to operate said mechanical means, a conduit carried by said helmet and communicating with the upper rear portion of said chamber, a blower operative to deliver outside air in a stream through said conduit and into said chamber, whereby the air stream is circulated through said chamber into contact with the person's hair and scalp and thence via said drain tube and back to the outside, and a heater operative to heat the air stream delivered through said conduit into said chamber.

16. The apparatus set forth in claim 15, wherein said sealing gasket is formed essentially of synthetic organic material that is characterized by being odorless and substantially completely impervious to warm water and heated air.

UNITED STATES PATENT OFFICE
CERTIFICATE OF CORRECTION

Patent No. 3,343,530

September 26, 1967

Louis P. Solos et al.

It is hereby certified that error appears in the above numbered patent requiring correction and that the said Letters Patent should read as corrected below.

Column 18, line 19, after "conduit" insert --
carried by said helmet and communicating
with the upper rear portion of said chamber,
a blower operative to deliver outside air
in a stream through said conduit and into
said chamber, whereby the air stream is
circulated through said chamber into contact
with the person's hair and scalp to dry
the person's hair and thence via said
drain tube and back to the outside, and a
heater operative to heat the air stream
delivered through said conduit into said
chamber --.

Signed and sealed this 8th day of October 1968.
